CLAIM

The ornamental design for a payment sensor for a parking meter, as shown and described.

DESCRIPTION

FIG. 1 is a front view of the payment sensor for a parking meter;

FIG. 2 is a right side view of the payment sensor for a parking meter;

FIG. 3 is a left side view of the payment sensor for a parking meter;

FIG. 4 is a top plan view of the payment sensor for a parking meter; and,

FIG. 5 is a front perspective view of the payment sensor for a parking meter.

The broken lines are for the purpose of illustrating location of the cover and form no part of the claimed design.
